(Model.)

A. W. CLARK.
CAR COUPLING.

No. 249,898.

Patented Nov. 22, 1881.

UNITED STATES PATENT OFFICE.

ASHER W. CLARK, OF MITCHELL, INDIANA.

CAR-COUPING.

SPECIFICATION forming part of Letters Patent No. 249,898, dated November 22, 1881.

Application filed July 23, 1881. (Model.)

To all whom it may concern:

Be it known that I, ASHER W. CLARK, a citizen of the United States, resident of Mitchell, in the county of Lawrence and State of Indiana, 5 have invented a new and valuable Improvement in Car-Couplers; and I do hereby declare that the following is a full, clear, and exact description of the construction and operation of the same, reference being had to the annexed 10 drawings, making a part of this specification, and to the letters and figures of reference marked thereon.

Figure 1 of the drawings is a representation of side view of my invention. Fig. 2 is an 15 end view of one of the cars. Fig. 3 is a bottom view, and Figs. 4 and 5 are detail views.

This invention has relation to improvements in automatic car-couplings; and it consists in the construction and novel arrangement of 20 parts, hereinafter set forth, and more particularly pointed out in the claims appended.

In the annexed drawings, the letter *a* designates a car, and *b* the bottom thereof, to which is secured, near its end, a block, *c*, which 25 is formed with the opening or bearing *c'*, which is provided with the slots or ways *c²* and *c³* at its ends. Passing through the opening *c'* is the rear extension, *d'*, of the draw-bar *d*, said extension having the longitudinal slot *d²*, in 30 which are seated the follower-plates *e e'*, the ends *e² e³* of which project through the slots *c²* and *c³*. Between these plates is located a spiral spring, *e⁴*.

The draw-bar *d* is provided at its forward 35 end with the draw-head *g*, which is formed with a central link-mouth, *g'*, and on one side of the same a recess, *g²*, having an open top, and designed for the attachment of the coupling-hook *h*, which is pivoted therein by the 40 transverse bolt *i*. A spring is placed on this bolt on each side of the hook *h*. On the other side of the link-mouth *g'* is a similar open-top recess, *g³*, having the bevel *f* and shoulder *h'* in front of said bolt *i*. Through the floor of this 45 recess is a slot, *h²*.

Attached to the hook *h* is a spiral spring, *k*, the upper end of which is secured to the crank or arm *l'* of a transverse shaft, *l*, pivoted to bearings on the end of the car, and having handles *o o*.

From the arm *l'* an operating-rod, *m*, having a series of holes, *m²*, extends through a

guide, *m'*, to the top of the car. In this manner means are provided for uncoupling the hook *h* from the top or sides of the car. The 55 spring *k* is designed to force the coupling-hook into engagement with the shoulder-catch *h'* of the opposite draw-head, and the action of the spring is rendered positive by means of the locking-pawl *n*, which is pivoted in bearings 60 at the end of the car, and is designed to engage one of the series of holes *m²* of the rod *m*. This pawl *n* is provided above with a handle, *n'*, and below is pivoted to a transverse operating-slide, *n²*, which is arranged in bearings 65 at the end of the car. A spring, *s*, serves to hold this pawl into engagement with the rod *m*, and thereby the position of the coupling-hook is varied to suit the necessities of the case.

The coupling-hook may be held thereby sufficiently high not to couple under any circumstances, or it may be held in proper position to couple with a high car, a low car, or a car on a level with that to which it is attached.

By locking the rod *m* the transverse shaft *l* is firmly held, and affords a bearing for the spring *k* as the hook *h* rises on the bevel of the catch-recess of the opposite draw-head, so that the action of said spring and hook is insured.

On each side of the draw-head is placed a spring, *z*, which springs hold the draw-head centrally, and yet allow the necessary play. Stops may be used to keep the springs from pressing the draw-head too far.

Having described this invention, what I claim, and desire to secure by Letters Patent, is—

1. In a car-coupling, a spring-actuated coupling-hook, an uncoupling device, and a locking mechanism, whereby the hook can be held at different positions, as set forth.

2. The combination, in a car-coupling device, with the hook *h*, of the spring *k*, the rod *m*, pawl *n*, and spring *s*, substantially as specified.

In testimony that I claim the above I have hereunto subscribed my name in the presence of two witnesses.

ASHER W. CLARK.
